UNITED STATES PATENT OFFICE.

JOHN H. McILVAINE, OF LAKE FOREST, ILLINOIS.

APPARATUS FOR BURNING LIQUID FUEL.

Application filed July 23, 1925. Serial No. 45,448.

This invention relates in general to proportional mixers, and more particularly one designed for use with liquid fuel or hydro-carbon burners, commonly known as oil burners; and while certain principles of my invention may be applied in the burning of any and all grades of fuel, the embodiment disclosed herein is intended for oil fuel of not lower gravity than 30° Baumé. My invention may be used for either industrial or domestic heating, its present application being to a furnace such as is used for heating the average home.

One of the objects of my invention is to improve the construction and operation of liquid fuel burners with the view to economizing in fuel consumption, cost of operation, and maintenance. This is accomplished by securing more efficient combustion and by employing a simple and novel operating and control mechanism.

My invention is characterized, primarily, by the provision for a continuous but variable flame having a sufficient range to burn from a low heat, without heating to any appreciable extent, to a high or maximum heat, and to intermediate heats sufficient to maintain the temperature desired in the average home under all conditions. In the broader aspect of my invention, however, the flame may be either continuous or intermittent, either constant in amount, or variable. In the practical application of my invention and in its preferred embodiment oil and air are fed in proper proportions and in certain predetermined amounts by an electric motor connected to a centrifugal pump and a centrifugal fan through suitable pipes to a combustion chamber. In my co-pending application, Serial No. 679,467, filed December 8, 1923, I employ a variable speed motor for driving the fuel pump and air fan and by varying the speed of the motor I vary the fuel feed. The present application is, however, confined primarily to the use of a constant speed motor for driving the fuel pump and air fan or blower and to the means whereby the fuel and air feeds are in proper proportions to maintain a continuous efficient flame throughout a wide range of heats as applied to practically any installation.

Some of the conditions and circumstances attending the use of the burner will better explain certain purposes and objects of my invention. The burner must be able to run at a flame sufficiently low so that practically no heat is given off on unseasonably warm days. The flame must be capable of rapid increase to give the proper amount of heat, in the event of a sudden drop of temperature, without blowing out. Also there must be a sufficient number of intermediate positions to properly control the house temperature. The burner must have sufficient capacity to keep the house at the average temperature desired such, for example, as 70° F. with the lowest outdoor temperature; and a high efficiency of combustion must be obtained at all loads. Moreover, outdoor variations of temperature and wind must not influence the amount of air supplied or the efficiency will be lowered due to either incomplete combustion or excess air. The burner should be adapted to manual control at the machine or remote control by means of a suitable thermostat, preferably one having three or more contact positions. Some of the advantages of the continuous variable flame will be readily recognized and appreciated. Inasmuch as the motor runs continuously there is practically no need for the usual starting coils, switches, and auxiliary devices and mechanisms invariably required for starting and stopping; consequently, the present construction is free from many of the troubles following from the use of intermittently operated oil burners. High combustion efficiency is also obtained by reason of the continuous flame. In the first place, at no time is any more heat being delivered into the heater or boiler than is necessary, with resulting relatively low temperatures of the stack gases at all loads, which means that the gases have given up more heat to the heater or boiler because they are never forced through faster than necessary. Also there are no idle periods as obtained with an intermittent flame and as a result the efficiency is increased. This is evident when compared with an intermittently operating system in which during a considerable period of time after the flame

starts, the combustion chamber, boiler and flues are comparatively cold and must be heated before the normal draft is reached, during which time insufficient air is supplied for proper combustion; and, after the intermittent flame ceases, the boiler and flues are very hot and continue to draw cold air through with resultant loss of heat. Another decided objection to the latter type 10 is that continually changing from a mere pilot light to a very high heat and back again, sometimes many times a day, puts a great strain on the heater or boiler and flues through rapid expansion and contraction, thereby causing cracks, leaks and displacements of the parts affected by the heat. The elimination of the gas pilot light or the electrical or combination ignition, absolutely prevents explosions through delayed ignition 15 or blowing out of the pilot light when the gas pressure is low. Still another advantage of the present invention as compared with the prior intermittently operating types of oil burners is that the number of mechanical parts is considerably reduced and the mechanism greatly simplified. It is believed that the present invention is a marked improvement over gravity type burners, especially in that more efficient combustion is obtained through positive feed of air at all loads which is little affected by changes of atmospheric conditions, as will be explained later.

In connection with the continuous flame 35 type of burner I have aimed especially to provide a simple and practical means for controlling and regulating the amounts of the air and fuel feeds. This control is characterized by its adjustment features where- 40 by in its application to practically any heater or boiler it may be adjusted and set to deliver such volumes of air at the different loads as to produce efficient combustion at all times. This is very desirable since in 45 practice there are hardly any two heaters or boilers in which the conditions affecting combustion are alike.

Other objects and attendant advantages 50 will be appreciated by those skilled in this art as the invention becomes better understood by reference to the following description when considered in connection with the accompanying drawings, in which—

Figure 1 is a side elevation of a liquid 55 fuel burner embodying my invention, showing its application to a heater or furnace such as used in homes;

Fig. 2 is an enlarged elevation of the apparatus, looking at the left hand side of 60 Fig. 1;

Fig. 3, is a similar view looking at the left hand side of Fig. 2;

Fig. 4 is an enlarged side elevation of the blower and air shutter control;

Fig. 5, is a section taken on the line 5—5 65 of Fig. 4;

Fig. 6, is a section taken on the line 6—6 70 of Fig. 5;

Figs. 7, 8 and 9, are top, side and dis- 75 charge end elevations, respectively, of the 70 combustion chamber or fire-pot; and

Fig. 10, is a diagrammatic view illustrating the system of burning the liquid fuel.

In considering my invention the liquid fuel will be referred to as oil. The oil flow will be first traced. The oil may be supplied from any suitable source such, for example, as from a storage tank (not shown) to a service tank 11. From this tank the oil flows by gravity through a shut-off valve 12, a strainer 13, and pipe 14 to a safety valve 15 adapted to shut off the flow to the burner in case of any failure of the flame as will be discussed later. The oil then flows through a pipe 15' to a float valve designated generally by 16 mounted on a suitable frame 17 and serving to maintain the oil at a constant level. From here the oil flows by gravity through a pipe 18 to a centrifugal pump 19 which is driven through a coiled spring connection 21 by a constant speed electric motor 22. Both the pump and motor are mounted on the frame 17 in the operative relation shown. The pump 19 is preferably of a special construction embodying the principles disclosed and claimed in my co-pending application, Serial No. 70,754, filed November 23, 1925. This pump has an oil inlet through the pipe 18 and an outlet through the upstanding pipe 23, and a rotary impeller 24. The revolving of the impeller raises the oil pressure to a head in the outlet pipe 23 and in a standpipe 25, as for example, to the level indicated by 26. Because the pump delivers a very small amount of oil as compared to its full capacity with unrestricted flow, the churning of the impeller causes the formation of small air bubbles which, being lighter than the oil, collect at the center of the impeller blade and tend to reduce the pressure of oil at the pump outlet. Provision is made for allowing escape of this trapped air as explained in my co-pending application claiming this pump construction. The pump friction load on the motor is practically eliminated by building the bearing for the impeller shaft without a stuffing box, which allows a very small amount of oil to flow continuously along the shaft and out of the bearing at a drip point 27. The further course of this drip will be discussed later.

The oil rises in the outlet pipe 23 by the action of the centrifugal pump and passes into the main standpipe 25 through a horizontal overflow pipe 28 which is higher than the level of the oil in the float valve 16. Thus, when the motor stops, the pump also stops, the oil level drops in pipe 23 below the

overflow pipe 28, and the oil flow ceases to the burner. When the motor is started the oil flows under pressure of the pump through the pipe 23 and 28 and into the main standpipe 25 which connects through pipe 29 to a control valve designated generally by 31. As this valve only allows passage of a certain amount of oil, small as compared to the full capacity of the pump, the level of the oil 5 rises in the standpipe until it reaches the above-mentioned point 26 above the overflow pipe 28, predetermined by the diameter of the impeller, the speed of revolution of the motor and the level of oil in the float valve. 10 This arrangement of standpipe 25, pipe 29 and control valve 31 allows all the air, as far as the control valve, to escape through said standpipe, and likewise allows the escape of any bubbles of air formed in the 15 pump and thrown out by the impeller blades into the upstanding outlet pipe 23. The control valve governs the amount of oil fed to the burner and may consist of a globe type needle valve with a threaded stem 32 on which an adjustment wheel 33 is mounted. On this stem 32 is mounted for adjustable connection with the wheel 33, as by a set screw 30, a lever arm 34 through which the valve is connected to an air control shutter which will be presently described. From the control valve the oil flows through a pipe 35 which rises to an overflow delivery point 36 from which point it drops through a vertical delivery pipe 37 having a sharp delivery point 38 from which the oil drops into the combustion chamber designated generally by 39. The rise at the overflow delivery point 36 allows a steady flow of oil and prevents gushing. Also the pipe 35 rises gradually to said overflow delivery point to allow the escape of air beyond the control valve 31. The purpose of the sharp delivery point 38 is to allow the oil to drop off into the combustion chamber 39 in a fine steady stream even at a very low rate without breaking up 45 into large bubbles which would cause an intermittent and jerky flame with poor combustion resulting. In order to prevent premature vaporization of the oil in the oil-delivery pipes they are enclosed in the air delivery pipe 41 and also in a vertically disposed portion 42 in which the vertical delivery pipe 37 is held centered so as not to come in contact with the air-delivery pipe which leads to the combustion chamber. The vertical oil-delivery pipe 37 at its upper extremity may be vented by connecting through suitable pipes to the atmosphere at any suitable place, thus allowing the oil to flow freely by gravity from the overflow point 36 to the sharp delivery point 38 without any siphonic action. I prefer however, to have a lateral opening 43 facing into the column of air flowing through the air delivery pipe 41, which arrangement assures a positive 50 feed of oil down through the pipe 37 and also assists in breaking up the oil into small particles at the sharp delivery point 38, thus improving combustion especially at high loads. The oil leaking out of the pump bearing at the point 27, as stated above, drops into a pipe 44 from the bottom of which a small coiled copper tubing 45 leads to the main oil delivery pipe line 35 beyond the control valve 31, from whence the drip 55 oil flows with the main oil supply to the combustion chamber. The small sized tubing 45 functions as a damper and prevents sloshing back and forth of the body of oil between the level in pipe 44 and the overflow 60 delivery point 36. The various parts of the apparatus are so arranged that the drip point 27 is sufficiently above the delivery point 36 to allow the pump leak oil to go to that point by gravity even when the air pressure in the air delivery pipe 41 reaches its maximum. Note that the drip point is about on a level with the armature shaft of the motor 22; that is, at about the center of the blower housing 48 (see Figs. 1 and 2). 65

The air delivery and control thereof is as follows: The motor 22 has a shaft extension 46 on the end opposite from the oil pump 19 on which is mounted a centrifugal fan or blower wheel 47 which revolves in a blower housing 48 and which delivers air under low pressure to the air delivery pipe 41 leading to the combustion chamber 39. On the inlet side of the blower housing is mounted a plate 49 enclosing the blower wheel blades 51 and having a central air inlet opening 52. The device for controlling the air supply to the blower, and consequently to the combustion chamber, consists of a stationary shutter having a stationary part 53 bolted to the intake side of the blower housing and a movable part 54 mounted for rotative movement on a bolt 55 passing through and supported by the stationary part 53. A coiled compression spring 56 on the inner end of the bolt 55 acts through the latter to hold the movable shutter part 54 seated against the stationary part 53 so as to prevent leakage of air to the blower inlet opening 52 through the contact surfaces of the two shutter parts. The stationary shutter part has two diametrically opposed open quadrants 57 and 58 and intermediate closed quadrants 59 and 61. The movable shutter part comprises diametrically opposed closed quadrants 62 and 63 and intermediate open quadrants complementary to the open quadrants 57 and 58 in the stationary shutter part. The open quadrants in the movable shutter part are graduated in size, comprising openings 64, 65 and 66 at one side of the shutter and 67, 68 and 69 at the opposite side and each is adapted to be closed to a variable degree by a plate held in position on the shutter part 54, in this case by screws 71, said plates being 70 75 80 85 90 95 100 105 110 115 120 125 130

numbered 72 to 77 inclusive. When the movable shutter part 54 is in the closed position, that is, with the two quadrants containing the openings 64 to 69 inclusive opposite 5 the closed quadrants 59 and 61 of the stationary shutter part, no air may pass to the blower inlet opening 52 through the shutter. In this position the blower fan wheel merely revolves in the housing and delivers no air 10 to the combustion chamber 39 except what reaches the blower housing through the opening for the fan wheel shaft and, in addition, through a series of small, low load inlet holes 78 in the stationary shutter part 53 which 15 may be plugged or opened to allow the proper amount of air to enter for supporting combustion at low load. The amount of air admitted to the blower at different successive positions of the movable shutter part 20 may be varied by the position of the respective plates 72 to 77 inclusive. This adjustment is made when installing or setting up the apparatus for the purpose of securing the desired amount of air in proportion to 25 the fuel feed at the different loads, as will be presently explained.

It is one of the purposes of my invention to connect the air and oil controls so that they are dependent one on the other for 30 operation and will consequently maintain a predetermined relative proportion between the air and oil feeds. The connection between the movable shutter 54, which controls the air delivery, and the oil control valve 31 35 comprises, in this instance, a link 79 pivotally connected at one end 81 to a bracket arm 82 radially adjustable on the shutter part 54 by adjustment of screws 83, and at its opposite end 84 to the lever arm 34 above- 40 mentioned, on the stem 32 of the oil control valve. The lever arm is adjustably connected to the stem 32, in this instance by a set screw 30 which clamps against the periphery of a hand wheel 33 fixed to said stem. 45 The oil feed at low load is determined by setting the control valve 31 (by adjustment of the set screw 30) when the movable shutter part 54 is in the closed position. By reason of the foregoing construction the air 50 and oil feeds will be simultaneously opened and closed in predetermined relative relation so that the proportions of the oil and air will be correspondingly controlled. According to my invention the air feed or delivery is variable at different loads to suit 55 the conditions peculiar to each installation, in some of which greater or less amounts of air may be required at the intermediate or higher loads in proportion to the fuel 60 feed, in order to assure complete and efficient combustion at the different loads. This variable air feed is obtained by adjustment of the shutter parts for 65 varying the size of the air inlet openings. It will now be observed that the shut-

ter openings 64, 65 and 66 are located diametrically opposite from the plates 75, 76 and 77, respectively, and that the openings 67, 68 and 69 are similarly located with respect to the plates 72, 73 and 74. This arrangement is designed to permit adjusting and setting the air shutter or control so that the proper proportions of air will be delivered to the combustion chamber at each load, regardless of the varying conditions 70 incidental to each installation. For example, when the shutter part 54 is moved in a counter-clockwise direction from said closed position the oil control valve 31 will be further opened and the air inlet opening 64 will uncover part of the top left open quadrant 57, thus allowing more air to enter the blower. The relative proportions of the oil and air feeds at this first position are, however, accurately determined to suit the draft and other conditions at hand, in the following manner: When the opening 64 is fully open and the opening 67 is just about to uncover part of the lower right open quadrant 58, a greater amount of air will be admitted through said opening 54 than is necessary for supporting proper combustion of the oil delivered at this position. The plate 72 will then be slid over part of the opening 64 to cut down the air supply to the correct amount and will then be locked in such position by the screws 71. Similarly, a further movement of the shutter part 54 in the same direction will move the next succeeding opening 67 to the full open position at which the following opening 65 will be ready to uncover the opening 57. The plate 75 will then be adjusted to cut down the air supply for this position in the same manner as when setting the plate 72. In like manner the remaining plates 73, 76, 74 and 77, will be adjusted in order. The air and oil feeds may be manually controlled as by manipulation of the wheel 33 on the oil control valve or the handle 85 on the movable shutter part; or, in the event that automatic control is desired, a suitable thermostat regulator 86 is provided, in this case mounted on the frame 17 below the motor, blower, etc., and connected to the movable shutter 115 part by a link 87.

The combustion chamber per se and the method of burning the liquid fuel or hydrocarbon therefor, forms the subject matter of my companion application for Letters 120 Patent, Serial No. 54,861, filed September 8, 1925, but will be described herein in order to convey a clear understanding of the present invention. This combustion chamber is designed to fulfill the requirements of a continuous flame burner which are discussed above, and its construction is an important factor to the present invention. The mixing or combustion chamber is, in its preferred embodiment, a casting, the shape of which 125

is best shown in Figs. 7, 8 and 9. The vertical air-delivery pipe 42 fits into the inlet end shoulder 89 of the combustion chamber casting which has an air inlet opening 91 rectangular in cross-section. The combustion chamber is defined by a vertical back wall 92, a vertical side wall 93 at right angles to the back wall; an opposed side wall which is curved in a vertical plane, as seen in Fig. 9, 10 and at an acute angle to the back wall in a horizontal plane, as seen in Fig. 7, a slanting bottom wall 95 making an acute angle with the back wall 92, as seen in Fig. 8, a low load pocket 96 extending out from the side wall 93 contiguous to the back wall, an outlet opening 97 which is preferably circular as shown, and a top wall forming a hood over the outlet opening. The combustion chamber is supported in an upright position 20 by suitable legs 98 integral with the casting, which rest on a base 99 which in turn rests on the furnace grates 101 over which a layer of fire brick 102 is placed for protection. The combustion chamber may, however, be 25 supported in any suitable manner in a furnace or heater according to the particular installation.

The operation is as follows: The blower and pump, driven at a constant speed by the 30 motor, will deliver air and oil to the combustion chamber, as described above. The air and oil enter the interior of the combustion chamber through the opening 91. Oil drops by gravity from the delivery point 38 35 to the slanting bottom wall 95 and runs down to the lowest point of intersection of the bottom wall 95, back wall 92 and pocket 96, or what I have termed the vaporizing point 103. When initially starting the burner it 40 is necessary to preheat the combustion chamber as by means of a gas torch, gas flame, oil soaked waste, or the like for vaporizing and igniting the oil. After the burner is thus started the heat from the combustion of the 45 oil will maintain a temperature high enough to thereafter effect vaporization of the oil and to produce a continuous flame, dependent of course, on continuous air and oil feed. The air jet coming through the inlet opening 50 91 passes down along the side wall 93, impinges against the slanting bottom wall 95, and mixes with the vapor at said vaporizing point 103. Here the mixture splits into two parts, the smaller of which enters the pocket 55 96 where combustion begins with a spinning flame, thus supplying heat to the metal of the combustion chamber near said vaporizing point. At low loads the burning mixture in the pocket 96 constitutes a large percent- 60 age of the total combustion, in fact, the pocket functions as though it were a small auxiliary combustion chamber enabling a very low rate of oil consumption without the flame being blown out or without the metal becoming too cold for vaporization, thus

making a separate form of gas or electric pilot light ignition, or other lighting means of this sort, unnecessary. The flame in pocket 96 emerges horizontally from the top half of the pocket and continues along that 70 part of the back wall 92 at the rear of the pocket. This flame spins, as shown by the arrows, and joins the rest of the burning mixture along the lower part of the back wall 92. As the amounts of oil and air are 75 increased, the proportion of the burning mixture in pocket 96 becomes less and less of the whole, but is always sufficiently large enough to supply heat to the metal at the vaporizing point 103, at which point at high loads a 80 small film of oil forms and spreads out along the intersection of back wall 92 with the bottom wall 95 and into the bottom of said pocket 96. Because the incoming air jet impinges at an abrupt angle to the surface of the oil film, the carbon residue is 85 burned up as fast as it is formed. The main portion of the mixture at higher loads turns away from the pocket 96, along the bottom wall 95 and then up along the curved side wall 94. The burning mixture is thus caused to whirl or revolve in the combustion chamber, as indicated by the arrows, but is held back in the chamber to some degree by the 90 inclined bottom wall 95 so as to prolong the vaporization period in the combustion chamber, thus tending to promote more thorough and complete combustion. The outlet opening 97 is located at the front of the combustion chamber, tangential to the top wall. 95 The effect of this construction is to hold the revolving or whirling burning mixture in the combustion chamber but at the same time allow it a smooth escape through the outlet opening 97 which, it will be observed, is 100 hooded at the top to throw the flame out horizontally and to keep it as low as possible in the combustion chamber of the furnace. The shape and proportions of the combustion chamber 39 are such as to eliminate the 105 formation of carbon deposit at any and all loads, to secure a thorough mixing of the fuel vapor and air, to give a clean white flame at all loads, and to reduce the noise usually produced by the rapid combustion at high loads. The vertical mounting of the combustion chamber gives a horizontal flame which is never long enough, even at high loads, to touch the cold boiler surfaces (in 110 application to a boiler), but which throws out the hot gases of combustion so that they 115 impinge on and utilize the lower surfaces of the boiler. In boilers where the flues are opposite the coal door, a fire brick baffle wall is placed a short distance in front of the combustion chamber to deflect the hot gases and throw them out at the side and top so that they will impinge on these surfaces of the boiler. 120 A pipe 104 leads from the base 99 to a 125

6
trip bucket 105 which actuates the safety valve 15 above-mentioned. In case of any failure of the flame, oil fills in the combustion chamber 39, runs out into the base 99 and partly fills the bucket 105 which then trips the valve 15, thereby shutting off the supply of oil to the furnace. The safety valve may also be actuated by overflow or leakage of oil into the drain pan 106 from which the oil flows through pipe 107 to the bucket 105.

In use, in order to minimize the change of the chimney draft produced by changes of outdoor conditions, the usual check draft door 15 in the furnace is opened to an amount equal in area to three or four times the area of the combustion chamber inlet opening 91. As the total area of the low load inlet holes 78 and shutter air inlet openings is smaller than 20 the area of opening 91 at low loads, the effect of changes of draft are reduced to a negligible amount by this opening of the check draft. As the load is increased, the total shutter inlet opening becomes greater, but 25 the air pressure in the air delivery pipe 41 then becomes so high in comparison to the chimney draft that the changes in outdoor atmospheric conditions have a negligible effect.

30 It is believed that the foregoing conveys a clear understanding of the objects prefaced above and, while I have illustrated but a single working embodiment, it should be understood that many changes might be 35 made in details of construction and in the construction and arrangement of the several units and instrumentalities as may be required in different applications and for furnaces or heaters of different types without, however, departing from the spirit and 40 scope of the invention as expressed in the appended claims, in which—

I claim:

1. Fuel burning apparatus comprising, in 45 combination, a combustion chamber, a blower for delivering air, means for delivering fuel to said combustion chamber, a control valve for regulating the feed of fuel delivered by said means, an air inlet control for the blower comprising a plurality of separately adjustable shutter elements arranged to be adjusted one after another to secure a desired proportion of air to fuel at different loads, and means connecting said air inlet control 50 and fuel feed control to maintain a determined relation between the amounts of air and fuel delivered to the combustion chamber at different loads.

2. Apparatus for burning gaseous or vaporized fuel comprising, in combination, a combustion chamber, a blower for delivering air, means for delivering fuel to said combustion chamber, a control valve for regulating the feed of fuel delivered by said 55 means, an air inlet control shutter for the

blower, means connecting said shutter and fuel feed control to maintain a determined relation between the amounts of air and fuel delivered to the combustion chamber at different loads, and means on said shutter 70 for varying the amounts of air admitted to the blower with respect to the fuel feed at different loads.

3. Apparatus for burning liquid fuel comprising, in combination, a combustion chamber, a constant speed motor, an air blower and a centrifugal oil pump constantly driven by said motor and connected to deliver air and oil into the combustion chamber, a control valve for the oil delivery feed, a control 75 valve for the air delivery feed comprising a plurality of parts arranged for separate adjustment for different operating loads, and means connecting said valves to determine the relative proportions of air and oil delivered to the combustion chamber at the different loads, the parts of the air control valve permitting independent adjustment of the air feed for every step by step adjustment 80 of the oil feed.

4. Apparatus for burning liquid fuel comprising, in combination, a combustion chamber, a constant speed motor, an air blower and a centrifugal oil pump constantly driven by said motor and connected to deliver air 95 and oil into the combustion chamber, a control valve for the oil delivery feed, a control valve for the air delivery feed comprising a shutter plate, means connecting said valve and plate to determine the relative proportions of air and liquid fuel delivered to the combustion chamber at the different loads, and means comprising a plurality of separately adjustable shutter pieces on said plate, each being arranged to be set for a given 100 operating load, for varying the amounts of air delivered to the combustion chamber with respect to the amounts of oil delivered there- 105 to at the different loads.

5. A fuel burning apparatus, means for 110 feeding fuel, and mechanism for delivering air under pressure to a combustion chamber including a shutter control for the air operated in synchronism with the fuel feed control, said shutter including variable openings for varying the amounts of air increase with respect to the fuel increase at different loads.

6. A fuel burning apparatus, means for 115 feeding fuel, and mechanism for delivering air under pressure to a combustion chamber including a shutter control for the air operated in synchronism with the fuel feed control, said shutter having variable air 120 openings.

7. A fuel burning apparatus for producing a constant flame variable to high and low loads comprising, in combination, a combustion chamber, a constant speed motor, an air blower driven thereby and a fuel line 130

for delivering air and fuel to said combustion chamber, an air inlet shutter for the blower comprising, in effect, a plurality of air valves and a plurality of air openings controlled thereby, each valve being separately adjustable to suit a particular operating load, a control valve for the fuel, and a control connection between said shutter and valve for determining the proportions of air and fuel 10 at the different operating loads.

8. A fuel burning apparatus for producing a constant flame variable to high and low loads comprising, in combination, a combustion chamber, a constant speed motor, 15 an air blower driven thereby and a fuel line for delivering air and fuel to said combustion chamber, an air inlet shutter for the blower, a control valve for the fuel, and a control connection between said shutter and 20 valve for determining the proportions of air and fuel at the different operating loads, including means for varying the air delivery with relation to the fuel feed at said different loads without affecting the proportion 25 of air to fuel at other loads.

9. Fuel burning apparatus comprising, in combination, a combustion chamber having fuel delivery means therefor, and means for delivering air to said chamber including 30 a blower for delivering air having a shutter comprising a stationary part and a movable part, the stationary part having diametrically opposed air inlet quadrants and the movable part having closed quadrants adapted to normally close said inlet 35 quadrants and also having a plurality of air inlet openings and means for varying the size of said openings, said air inlet openings being arranged to be moved in succession 40 into registration with said air inlet quadrants by operation of the movable shutter part.

10. In a burner, in combination, a combustion chamber, and means for delivering 45 fuel and air to said chamber in determined relative proportions throughout the range of operation from low to high loads including several separately adjustable means for varying the relative proportions of air to fuel at low and high loads as well as at any intermediate load, the said means permitting an independent adjustment of the air feed for every step by step adjustment of the fuel feed to insure the proper proportioning of the two for all loads within the range of operation.

11. In an oil burner, in combination, a combustion chamber, and means for delivering oil and air to said chamber in determined relative proportions throughout the range of operation from low to high loads including several separately adjustable means for independently varying the relative proportions of air to oil at low and high loads as well as at any intermediate

load, the said means permitting an independent adjustment of the air feed for every step by step adjustment of the oil feed to insure the proper proportioning of the two for all loads within the range of operation. 70

12. In a fuel burning apparatus, in combination, a combustion chamber, and means for delivering air to said chamber in regulated volumes including an air control shutter having plural series of air inlet 75 openings and an adjustable closure for each opening, said openings being arranged to open in succession, alternating from one series to another.

13. In a fuel burning apparatus, in combination, a combustion chamber, means for delivering fuel and air to said chamber including a fuel control valve and a blower, the blower having an air inlet shutter, said shutter having plural series of air inlet 80 openings and an adjustable closure for each opening, said openings being arranged to open in succession, alternating from one series to the other, and means whereby the fuel control valve and air shutter will be 85 operated to deliver determined proportions of fuel and air at various loads to the combustion chamber.

14. In a fuel burning apparatus, in combination, a combustion chamber, a valve for 90 furnishing fuel to the combustion chamber means for delivering air to said chamber for supporting combustion including a blower having a shutter for controlling the air inlet, means for admitting air to the 100 blower when the shutter is in the closed position for supporting combustion in said chamber when the fuel valve is in the low position, said shutter having plural series 105 of air inlet openings and an adjustable closure for each opening, said openings being arranged to open in succession, alternately from one series to the other.

15. In combination with a furnace, an air control including a shutter having a relatively fixed and a movable part, the latter being adjusted for proportioning the air supply with respect to the fuel supply, the fixed part being open for the admission of air, the movable part normally closing 110 the opening in the fixed part and having plural series of air inlet openings and an adjustable closure for each opening, said openings being arranged to be moved in succession over the opening in the fixed 115 part, the successive order alternating from one series to the other.

16. In combination, a combustion chamber, a valve controlled means for delivering air to said chamber for supporting combustion, said air valve comprising pivotally connected parts, one stationary and the other rotatable, the stationary part having diametrically opposed air inlet quadrants and the rotatable part having diametrically 125 130

CERTIFICATE OF CORRECTION.

Patent No. 1,654,658.

Granted January 3, 1928, to

JOHN H. McILVAINE.

It is hereby certified that error appears in the printed specification of the above numbered patent requiring correction as follows: Page 6, lines 59 and 60, claim 2, strike out "Apparatus for burning gaseous or vaporizing fuel" and insert "Fuel burning apparatus"; page 6, lines 110 and 119, claims 5 and 6, strike out the article "A" and insert instead "In a"; and that the said Letters Patent should be read with these corrections therein that the same may conform to the record of the case in the Patent Office.

Signed and sealed this 31st day of January, A. D. 1928.

Seal.

**M. J. Moore,
Acting Commissioner of Patents.**
